ABRADING MACHINE

Harold N. Seyferth, East Detroit, Mich., assignor to Ex-Cell-O Corporation, Detroit, Mich., a corporation of Michigan

Application October 10, 1950, Serial No. 189,372

13 Claims. (Cl. 51—101)

1

The invention relates to machines for finishing workpieces having complex curves surfaces, and it is more particularly concerned with machines in which the finishing is effected by the abrasive action of a tool on the workpieces.

The machine of the present invention, while capable of finishing workpieces of a wide variety of shapes, is particularly well adapted for finishing turbine blades that have been previously machined to the desired shape and approximately the finished dimensions by a machine such as that disclosed in my copending application Serial No. 189,371, filed October 10, 1950. In the machine referred to, the blade is shaped by taking a series of closely spaced longitudinal cuts with the spacing of the tool and work controlled by cam means so as to generate the desired surface contour.

The primary object of the present invention is to provide a machine by which the tool marks and excess stock left on the workpiece in the shaping operation can be removed quickly and efficiently to produce a finished turbine blade precisely dimensioned and smoothly finished.

Another object is to provide an improved turbine blade finishing machine which reduces loading and unloading time, as well as operating time, thus enabling the blades to be produced quickly and at minimum cost.

Still another object is to provide a machine for finishing curved surface workpieces arranged to employ a novel cam having a surface of revolution completely free of abrupt rises or falls and capable of being produced easily and cheaply from a master pattern, exhibiting the surface to be reproduced.

A further object is to provide controls for machines of the above general character which renders their operation substantially automatic.

Other objects and advantages of the invention will become apparent from the following detailed description of the preferred embodiment illustrated in the accompanying drawings, in which:

Figure 1 is a perspective view of a machine embodying the features of the invention.

Fig. 2 is a perspective view of a typical article adapted to be finished by the machine, the article being a turbine blade.

Fig. 3 is a sectional view taken in a vertical plane through the axis of the work holding spindle and showing the tool slide in elevation.

Fig. 4 is a sectional view of the work supporting frame with the tool slide, the work holding spindle and associated elements shown diagrammatically.

2

Fig. 5 is a fragmentary elevational view of the machine as viewed from the left end.

Fig. 6 is a fragmentary plan view of the outer end of the work holding spindle and the controls associated therewith.

Fig. 7 is a fragmentary elevational view of the machine as viewed from the right end.

Fig. 8 is a sectional view taken in offset planes substantially on the line 8—8 of Fig. 7.

Fig. 9 is a sectional view taken in a vertical plane substantially on the line 9—9 of Fig. 7.

Fig. 10 is a diagrammatic view showing the relative positioning of the tool and workpiece.

Fig. 11 is a schematic diagram of the hydraulic circuit of the machine.

Fig. 12 is a schematic diagram of the electrical circuit of the machine.

While the invention is susceptible of various modifications and alternative constructions, I have shown in the drawings and will describe in detail the preferred embodiment, but it is to be understood that I do not thereby intend to limit the invention to the specific form disclosed, but intend to cover all modifications and alternative constructions and uses falling within the spirit and scope of the invention as expressed in the appended claims.

Referring to Figs. 1, 3 and 5 of the drawings, the exemplary machine comprises a generally rectangular box-like base 20 from which rises an upright frame including a pair of end members 21 and 22 joined adjacent their upper ends by an inwardly offset vertically disposed web 23. Extending between the end members below the web is an inclined apron 24 which serves to direct metal chips and liquid coolant through an opening 25 in the top wall of the base 20 into a compartment or sump within the base.

Supported on the machine frame at the front thereof is a tool spindle and drive assembly 26. This assembly may be of conventional construction and, as shown more clearly in Fig. 3, comprises a base member 27 bolted or otherwise suitably secured to the web 23 of the frame. The base member 27 is formed with suitable ways for supporting and guiding a slide 28, at the upper end of which is journaled a rotary spindle 29 which projects at one side of the slide and carries a suitable abrasive tool, in this instance a grinding wheel 30. Also mounted on the slide 28 is a motor M arranged to rotate the spindle 29 at high speed through the medium of a driving belt 31. As shown in Fig. 1, the belt and associated rotating elements are enclosed in a coolant and chip-proof guard 32.

While as indicated above the exemplary ma-

chine is shown equipped with a rotary grinding wheel, it will be appreciated that other types of abrasive tools such as abrasive belts or the like may be employed if desired. When equipped with the type of tool illustrated, the spindle and drive assembly 26 is mounted so that the slide 28 is adjustable in an inclined but generally vertical path for varying the effective height of the wheel 30. The spindle 29, in this instance, is arranged transversely of the path of adjustment so that its axis is in intersecting right angularly disposed planes, one of which is vertical and the other inclined to the horizontal. The wheel 30 is mounted at the upper end of this spindle in a position so as to tangentially engage the surface 15 of the work and through adjustments of the slide compensation may be made for tools of different diameter.

Adjustment of the spindle slide 28 is effected in the present instance by means of a feed screw 20 (not shown) adapted to be rotated by a hand wheel 34 located adjacent the lower edge of the base member 27 or alternatively by a hand wheel 35 located adjacent one side of the base member. As shown in Fig. 1, the spindle and drive assembly is equipped with a wheel truing dresser 36 which may be similar to that disclosed in the patent to Gilbert D. Stewart, No. 2,351,159, issued June 13, 1944. Mechanism similar to that disclosed in the patent to M. A. Mathys, No. 30 2,310,977, issued February 16, 1943, may be provided for automatically adjusting the position of the grinding wheel after each truing action. As the dresser and adjusting mechanism form no part of the present invention, it is not believed necessary to describe them in detail, but reference may be had to the above noted patents for a description of their construction and mode of operation.

For supporting a workpiece W in operative relation to the grinding wheel 30, an auxiliary frame 40 is mounted at the top of the machine frame for oscillating or pivotal movement about a horizontal axis and for linear translation along said axis. Provision is made for holding the workpiece above the wheel 30 so that the pivotal movements of the frame 40 are effective to move the work toward or from the wheel and thus determine the depth of cut, that is, the amount of stock removed by the wheel. Rotation of the workpiece together with the traverse movements of the frame serve to present the entire work surface to the action of the wheel. To enable the machine to remove surface irregularities and excess material from the workpiece and produce a finished piece of precisely the desired dimensions, provision is made for rocking the frame on its pivot to vary the relative positions of the tool and work in timed relation to the rotation of the workpiece and its linear translation with the frame.

Referring to Fig. 2 of the drawings, the turbine blade W illustrated is typical of the type of work that can be finished by the machine of the invention. It has a transversely disposed root portion 41 shaped for mounting in a dovetailed slot and a blade portion 42 which is convex on one side and concave on the opposite side. The blade portion conventionally has relatively sharp leading and trailing edges and it may be twisted about its longitudinal axis to present a generally spiral configuration.

For machining purposes, the blade is initially formed with an integral lug 43 at the tip end and this lug center drilled for the accommodation of

a tail center which assists in accurately locating and supporting the blade during the machining process. The lug and the adjacent unfinished portion of the blade is cut off at a later stage of the manufacturing process.

Referring now to Figs. 3-5 of the drawings, the auxiliary frame 40 comprises an elongated top member 45 having depending flanges 46 and 47 at opposite ends. Support for the frame is provided by bearings 48 and 49 seated in the legs 46 and 47 and respectively engaging over opposite ends of an elongated rod 50. The rod 50 extends axially through a cylinder 51 formed in a bracket 52 rigidly supported on the rear portion of the machine frame. A piston 53 is fixed to the intermediate portion of the rod 50 within the cylinder. The opposite ends of the cylinder are closed by heads 54 apertured for the passage of the projecting ends of the rod so that the piston may be shifted back and forth within the cylinder by introduction of pressure fluid alternately into opposite ends of the cylinder. At least one of the bearings 48, 49 is confined against movement axially of the rod 50 so that the auxiliary frame 40 is constrained to reciprocate with the rod.

The bearings 48 and 49 in addition to affording an operative connection between the piston rod 50 and the auxiliary frame 40, also serve as trunnion bearings permitting the frame to pivot about the axis of the rod. Preferably this axis is located adjacent the rear edge of the auxiliary frame so that the weight of the frame tends to rock its forward portion downwardly or toward the tool spindle 29 which it overlies.

Referring now to Fig. 3 of the drawings, it will be noted that a depending flange or web 55 is provided on the underside of the top member 45 in parallel spaced relation to the end flange 46. These two flanges provide support for a rotatable work holding spindle 60 disposed with its axis parallel to and offset forwardly from the pivotal axis of the auxiliary frame.

In the exemplary machine the spindle 60 is formed at its inner end with an enlarged head 61 journaled in a bearing 62 seated in the flange 55. The other end of the spindle extends through a sleeve member 63 journaled in a suitable bearing seated in the flange 46.

The head portion 61 of the spindle is formed with an axial recess or socket 64 adapted to receive the shank portion of a chuck 65 which may be locked in place as by a set screw 66. The chuck 65 may be of the conventional type having opposed jaws operable to grip or release a workpiece. Actuation of the jaws is effected through the medium of a rod 67 extending through an axial bore in the spindle and projecting at the outer end thereof. A knob 68 on the projecting end is available for manipulation of the chuck.

In the particular embodiment of the invention illustrated, the work holding spindle 60 is non-rotatably coupled with the sleeve 63 as by a feather key 70 permitting relative axial movement of the parts. A coil spring 71 interposed between a shoulder 72 on the spindle and an opposed shoulder on the sleeve member urges the spindle to the right as viewed in Fig. 3.

The axial positioning of the spindle is determined by an annular cam 73 supported on the outer side of the flange 46 coaxially of the spindle 60 and having an axially facing bearing surface 74. This surface forms a track for a follower roller 75 journaled on a stud 76 projecting radially from a collar 77 rigidly fixed to the spindle. With this arrangement the spindle is adjusted

axially incident to its rotation as determined by the contour of the cam track 74.

In loading the workpiece W into the machine the root portion 41 is gripped in the jaws of the chuck 65. For supporting the other end of the workpiece there is provided a tailstock 80 having a center 81 engageable with the lug 43. The tailstock 80 may be similar in construction to that shown in my copending application above referred to. For present purposes it is sufficient to note that the center 81 is carried by a slide 82 supported for movement axially toward and from the workpiece. The slide may be shifted manually as by a hand lever 84 (Fig. 3) or by a pressure fluid operated actuator including a piston 85 operating in a cylinder 86 formed within the bracket 83.

To regulate the position of the work relative to the tool 30, that is, the radial distance of the peripheral or operating surface of the tool with reference to the axis of the workpiece, as the work is rotated and shifted axially relative to the tool, cam means is provided for rocking the frame 40 about its pivotal axis. The cam means includes a barrel type cam 90 having a surface of revolution 91 generated in conformity with a master pattern so as to represent the finished contour of the workpiece. Cam 90 is formed with an axial bore 92 adapted to slidably receive the work holding spindle 60 and is nonrotatably secured in fixed angular relation to the spindle by a dowel pin 93 carried by a collar 94 keyed to the spindle. A nut 95 threaded on the spindle and bearing against the end of the cam 90 remote from the collar 94 holds the cam securely against the collar and against axial movement relative to the spindle.

For cooperation with the cam 90 a follower roller 96 is mounted on the machine frame directly below the cam. As shown in Fig. 3, the follower roller is supported for rotation about an axis parallel to the axis of the work holding spindle adjacent the upper end of a slide 97 supported and guided in a bracket 98 bolted or otherwise rigidly secured to the frame member 21 of the machine. Provision is made for adjusting the vertical position of the follower roller as required for tools of different diameters. For this purpose a stop screw 98a (Fig. 4) threaded into the lower end of the slide 97 has its head positioned to engage a shoulder or abutment 99 formed on the bracket 89. The screw may be provided with a hand wheel 100 for convenience of manipulation.

Power actuated means is provided for shifting the slide 97 and follower roller 96 upwardly to raise the work supporting frame to a retracted position for convenience of loading and unloading the work. This power means also serves to control the rate at which the frame 40 is lowered to feed the workpiece to the tool.

As shown in Figs. 3, 4 and 11, the power actuated slide shifting means comprises a piston 101 working in a vertically disposed cylinder 102 formed in the bracket 98 below the abutment 99. The piston has a rod 103 projecting from the upper end of the cylinder and operatively secured in a suitable manner to the lower end of the adjusting screw 98. Introduction of pressure fluid into one or the other end of the cylinder 102 will accordingly raise or lower the frame 40 by pivoting the same about the axis of the rod 50.

In the finishing operation, it has been found desirable to effect a relative traverse of the tool and work transversely of the tool marks left by

the preceding operation. As the tool marks left by the milling operation extend longitudinally of the workpiece the preferred relative traverse is effected by rotation of the workpiece about its longitudinal axis. Provision is therefore made for rotating the work holding spindle 60 to effect such relative traverse while the work is shifted axially as by linear traverse of the frame 40 to present successive areas of the workpiece for the action of the tool. In practice these two movements are coordinated so that the tool, in effect, describes a spiral path around the work extending from one end to the other of the surface area to be finished.

Rotation of the spindle 60 is effected in the present instance by a motor M1 supported at one end of the frame 40. As shown in Fig. 5, a gear 104 on the motor shaft meshes with a pinion 105 keyed to a shaft 106. The shaft is journaled in a housing 107 which encloses the spindle supporting sleeve 63. As shown in Figs. 3 and 4, a worm 108 on the shaft cooperates with a worm wheel 106 keyed to the sleeve 63 to complete the driving connection.

Preferably the motor M1 is a variable speed motor capable of driving the shaft 106 at at least two different speeds. For example, when operating on relatively flat surfaces it is desirable to traverse the work relatively slowly past the tool, whereas a much faster traverse is desirable when the narrow edge of the workpiece is presented to the tool. Motor speed may be conveniently controlled by a control device such as a two position switch LS4 actuated in timed relation with the rotation of the spindle 60. For actuating the switch LS4 a control member or disk 110 (Figs. 4 and 5) is keyed or otherwise non-rotatably fixed on the projecting end of the spindle 60. Arcuate shoes 109 supported on the outer face of the disk 110 engage the switch to close switch contacts LS4-A for operating the motor at high speed. When the shoes are rotated out of engagement with the switch, contacts LS4-A open and contacts LS4-B are closed, thus initiating operation of the motor at a slower speed. As the exemplary workpiece has two narrow edges, two of the shoes 111 are provided in the illustrative embodiment. The shoes, of course, are spaced apart so as to change the motor speed at the proper time, in this instance, 180° apart as shown in Fig. 5.

The invention also provides novel control mechanism whereby complicated curved areas such, for example, as the fillet F joining the root portion 41 and blade portion 42 of the blade 55 may be finished with great precision. The peculiar tool and work movements required for such finishing will be appreciated when it is considered that the fillet in addition to following the general contour of the blade portion also follows the transverse alignment of the root portion. To impart the movements to the workpiece so as to engage the work and tool along this path, there is provided a work frame positioning cam 115 which supplements the spindle positioning action of the cam 73.

The cam 115 which is generally wedge shaped is interposed between an abutment or anvil 116 mounted on the flange 47 of the frame 40 and a stop element 117 mounted on an upstanding bracket 118 rigid with the machine frame. As shown in Fig. 8, the face of the cam engaging the anvil 116 is flat while the opposite face is contoured to provide an inclined area 119, a sub-

stantially flat dwell area 120, a second inclined area 121 and another flat dwell area 122.

At the beginning of a cycle the cam is located in the advanced position shown in Fig. 4, with the higher portion of the inclined area 119 positioned for engagement with the stop 117. As the frame 40 is urged to the right this cam surface engages the stop which thus determines the limit position of the frame. As the cam is withdrawn, the frame is allowed to advance slowly to the right and then is maintained in this position for an interval of sufficient length to permit a complete revolution of the workpiece. A further advance occurs as the inclined area 121 rides over the stop and there is a further dwell as the area 122 engages the stop. This latter dwell is preferably also of sufficient length to permit a complete revolution of the workpiece. The movements of the table occasioned by the cam 115 combined with the axial shifting of the work holding spindle 60 by the cam 73 enable the tool to follow and accurately finish the fillet F entirely around the blade.

For retracting the cam 115 in the manner above described, there is provided a pressure fluid operated actuator comprising in this instance a cylinder 123 supported on the flange 47 adjacent one end of the cam. A piston 124 working in the cylinder has a piston rod 125 formed at its outer end with a T-shaped head 126 engageable with a T slot 127 in the adjacent end of the cam. By introduction of pressure fluid into one end or the other of the cylinder 123 the cam may be shifted in either direction as required. The supply of pressure fluid is controlled by a solenoid operated valve V1 with which is associated a metering valve MV2 as shown in Fig. 11.

The pressure fluid operated actuators hereinbefore referred to are incorporated in a novel hydraulic system including suitable control valves and electrical operating and control devices for effecting operation of the machine in a completely automatic cycle. Pressure fluid for operating the actuators is supplied by a pump P driven by an electric motor M2. As shown in Fig. 11, the pump draws fluid from a sump or reservoir R by way of an intake conduit 130 and discharges it by way of a working pressure relief valve PRV to a branched pressure line 131. The pressure fluid is distributed to the various actuators under the control of valves whose operation can be best described in conjunction with a description of the electrical control circuits shown in Fig. 12 of the drawings. This control system is preferably operated at low voltage, operating current being obtained in this instance from a step-down transformer T having its primary winding connected across two of the leads of a three wire power line L which supplies current to the motors M, M1, M2 and M3. A switch S is provided in the power line L for shutting off all power to the machine when desired.

When the machine is to be placed in operation, a momentary closing of motor starting switch MS energizes relay MR. This relay completes a holding circuit for itself by closing switch MR-1 and closes switch MR-2 to start the pump driving motor M2 and the coolant pump motor M3. The tool spindle driving motor M is then started by closure of a switch MS1. This energizes a relay MR1 which completes a holding circuit for itself by closing switch MR1-1 and also closes switch MR1-2 to connect motor M across the line L.

Assuming that the machine is in a rest condition, the work supporting frame 40 will be at its right-hand limit position with the frame raised

to unloading position through the action of the actuator for the follower roller slide 81. The workpiece is accordingly loaded in the machine by placing the root portion in the chuck 65 and closing the chuck jaws by operation of the knob 68. Cycle selector switch CS is set manually in the automatic position in which it is shown in Fig. 12 with its upper set of switch contacts CS-1 open and its lower set of switch contacts CS-2 closed. Direction control DS switch is now set in its right position opening switch contacts DS-1 and closing contacts DS-2.

Limit switch LS1 is actuated as a result of the preceding movement to starting position so that switch contacts LS1-A open and switch contacts LS1-B are closed. Limit switch LS2 is held open by engagement therewith of a pin 132 cammed by the control disk 110 and LS3 is held open by a stop member 133 fixed to the piston rod 50 (Fig. 4). Limit switch LS4 is engaged by one of the shoes 111 on the disk 110 closing switch LS4-A and opening switch LS4-B. Limit switch LS5 has its switch contacts LS5-A open and switch contacts LS5-B closed due to the switch actuator 134 being in a raised position. This actuator is carried on an extension 135 of the lower end of the work frame camming piston 101.

An automatic cycle may now be initiated by momentary closure of cycle start switch CS-3. Closure of this switch completes an energizing circuit for control relay CR1 which completes a holding circuit for itself by closing switch CR1-1. Switch CR1-2 is closed to complete an energizing circuit for solenoid SV3 which shifts valve V3 to direct pressure fluid into the upper end of the cylinder 102. This pressure fluid circuit extends by way of conduit 140 which branches from the pressure line 131, conduit 141, valve V3, conduit 142, metering valve MV1 and conduit 143 to cylinder 102. Metering valve MV1 includes an adjustable orifice member 144 which determines the rate of flow of fluid to the cylinder and thus the rate of descent of the work supporting frame 40.

It may be appropriate to note at this point that when valve V3 is shifted to its alternate position by the biasing spring 145, cylinder 102 is connected to the drain 145 by way of the conduit 143 and through a check valve 146 in metering valve MV1, conduit 142, valve V3 and conduit 147 which is a branch of the drain 145. The metering orifice is thus by-passed so that the upward movement of the piston 101 and the work supporting frame is effected at a rapid rate.

Closure of switch CR1-3 completes a circuit by way of limit switch LS4-A for motor relay MR2 which closes switch MR2-1 to connect the work spindle driving motor M1 across the line L. In this operating circuit motor M1 runs at relatively high speed. An alternate or slow speed circuit is controlled by a switch MR3-1 of relay MR3 which is energized when limit switch LS4-B is closed.

As the workpiece approaches the tool 30, actuator 134 moving with the piston 101 actuates limit switch LS5 opening switch LS5-B and closing switch LS5-A. The opening of switch LS5-B interrupts the circuit for infeed cam solenoid SV2 and the closure of limit switch LS5-A completes an energizing circuit for outfeed cam solenoid SV1. The latter solenoid energizes and shifts valve V1 to direct pressure fluid to the inner end of the cam actuating cylinder 123. Pressure fluid flow is by way of a conduit 148 branching from the pressure line 131, valve

VI and conduit 149 extending to the inner end of the cylinder 123.

Fluid exhausted from the opposite end of the cylinder 123 is discharged by way of a conduit 150, metering valve MV2, conduit 151, valve VI and conduit 152 to drain 145. Fluid thus discharged is directed through a metering orifice defined by an adjustable member 153 which restricts the rate of flow and thus limits the withdrawal movement of the cam to a predetermined desired speed. The movement of the cam in the opposite direction is effected at a higher rate by reason of the by-pass around the orifice afforded by the check valve 154.

In finishing the particular workpiece illustrated, the metering valve is set to effect a withdrawal of the cam 115 at a rate such that the stop member 117 rides down the inclined surface 119 and engages the dwell 120 substantially as the work is brought into operative engagement with the tool. The dwell 120 is of sufficient length to permit the work to make a complete revolution wherein the fillet F is finished with the cam 73 cooperating in positioning the work with respect to the spindle. The stop then rides down the inclined surface 121 and engages the dwell 122 which also is of sufficient length to permit a complete revolution of the work.

Shortly before the cam 115 is shifted far enough to disengage the stop from the dwell 122, the actuator piston 124 uncovers a port connected by a conduit 155 with direction valve DV. The plunger of the valve DV is shifted to the left so as to direct pressure fluid through the conduit 156 to the right end of the cylinder 51 and thus initiate feed of the work supporting frame 40 to the left. The workpiece is therefore traversed longitudinally relative to the tool and at the same time is rotated continuously by the motor M1. As described heretofore, the motor speed is regulated in accordance with the requirements of the particular surface area being finished by alternate operations of the limit switches LS4-A and LS4-B.

Fluid flow to the cylinder 51 is by way of the conduit 140, branch conduit 157, valve DV and conduit 156. Fluid is exhausted from the other end of the cylinder by way of a conduit 158, metering valve MV3, conduit 159, metering valve MV4, conduit 160, valve DV to drain 145. Metering valves MV3 and MV4 are respectively fitted with adjustable orifice members 161 and 162. In the present setup the orifice member 162 is adjusted to provide a relatively slow feed properly coordinated with the rotative speed of the work to enable the tool to operatively engage the entire area of the workpiece. Orifice member 161 which is set for a substantially higher rate of feed has no effect upon the operation of the machine in this particular cycle.

Movement of the work frame 40 to the left continues until the tool reaches the end of the surface being finished, at which time limit switch LS1 is actuated to open normally closed contacts LS1-B. Actuation of the limit switch may be effected in any suitable manner as an incident to the table approaching its limit position as, for example, by means of a stop element 165 fixed to the spindle 50, as shown in Fig. 4. With limit switch LS1-B open the next opening of limit switch LS2 by the pin 132 on disk 110 as the work is rotated to an unloading position results in the deenergization of control relay CR1. Relay CR1 open switch contacts CR1-2 deenergizing solenoid SV3. This permits the valve V3 to shift under 75

spring actuation to its table raising position, wherein the upper end of the cylinder 102 is connected to drain, thus allowing the piston 101 to raise the table rapidly to the unloading position.

5 The opening of switch contacts CR1-3 interrupts the circuit for either of the motor relays MR2 or MR3 which may be energized at this time. As a result the work spindle driving motor M1 is stopped.

10 Switch contacts CR1-4 are also opened, de-energizing solenoid valve SV1. As the work frame 40 moves upwardly, limit switch LS5 is disengaged from the actuator 134 opening switch contacts LS5-A and closing switch contacts LS5-B. Closure of the latter switch contacts completes an energizing circuit for solenoid SV2 which shifts valve VI to direct pressure fluid to the cylinder 123 to effect inward feed of the cam 115. As previously explained, such inward movement takes place at a rapid rate.

15 As the cam 115 approaches its inner limit position, piston 124 opens a port connected by a conduit 166 with the direction valve DV, thus directing pressure fluid to the right end of the valve and shifting the valve plunger into a position to initiate feed of the work supporting frame 40 in the opposite direction or to the right. This movement takes place at a rapid traverse rate since the fluid flow to the left end of the cylinder is by-passed around the orifices 161 and 162 by way of the check valves 167 and 168 associated therewith. As the work supporting frame reaches its right limit position, limit switch LS1 is actuated by the stop member 133 to deenergize control relay CR1. Deenergization of control relay CR1 brings the machine to a complete stop with the work supporting frame in the raised position, so that the work may be unloaded and a new workpiece loaded therein.

20 At times it may be desirable to provide for rapid traverse movements of the work supporting frame 40 in the same direction as the feed movement. Under such conditions a limit switch LS3 is arranged for actuation by or in response to the movement of the frame to a predetermined position. Closure of switch LS3 energizes a solenoid SV4 which shifts a pilot valve PV to operate a valve V4 to its alternate position. Valve V4 when so operated establishes a by-pass around the metering valve MV4 by connecting conduit 159 with conduit 160 by way of conduits 169 and 170. Upon opening of the switch LS3 solenoid SV4 is released and the pilot valve is returned by a spring to reset valve V4 for feed operation.

25 The control system may be readily changed to adapt the machine to start grinding at the tailstock end of the workpiece rather than at the headstock end, as above described. To effect such operation, the conduits 155 and 166 leading from the cylinder 124 to the direction valve DV are reversed. Additionally the direction selector switch DS is operated to the left position, closing switch contacts DS-1 and opening switch contacts DS-2. The driving motors are started in the manner heretofore described by closure of the motor switch MS and the cycle is started by closure of the cycle starting switch CS-3. In this case, however, control relay CR1 completes its holding circuit by way of switch CR1-1, direction switch DS-1 and a switch TR1 closed by a delayed action relay TR. This relay is energized by closure of a limit switch LS1-A incident to the work supporting frame moving to its left-hand limit position. Operations then proceed in substantially the manner above described.

The control circuits may also be conditioned for manual control by operating the cycle control switch CS to its alternate position, closing switch CS-1 and opening switch CS-2. When set for manual operation inward movement of the feed control cam 115 is initiated by closure of control switch CS4. Outward movement of the cam switch is initiated by closure of control switch CS5. Automatic control of the cam is precluded by the opening of control switch CS6. Closure of control switch CS7 permits the work spindle driving motor M1 to be started and stopped manually by closure of a switch CS8. To permit such operation, a manually settable switch is first actuated to the manual control position, closing switch CS9 and opening switch CS10.

The machine may be stopped at any time regardless of the setting of the cycle selector switches by opening a normally closed master stop switch SS1. Likewise, the tool spindle motor may be stopped by actuation of a stop switch SS2 and, when the machine is set for automatic operation, the cycle may be interrupted at any time by opening a stop switch SS3. In the latter instance the cycle may be restarted at the point of interruption by momentary closure of control switch CS3.

It will be apparent from the foregoing that the invention provides an abrading machine of novel and advantageous character, particularly well adapted for finishing workpieces having complex curved surfaces. The machine is easy to load and unload and is rapid and efficient in operation. Through the medium of the novel operating and control systems incorporated in the machine, the manual labor involved in the finishing of workpieces such as turbine blades is practically eliminated and the time required for finishing such workpieces is substantially reduced. Overall costs of such operations are thus held at a low figure.

I claim as my invention:

1. In a machine for operating on workpieces having complex curved surfaces of revolution, in combination, a base, a slide mounted on said base, a driven abrasive tool carried by said slide, a frame supported on said base for pivotal movement about an axis disposed at one side of said tool and for linear translation along said axis, work holding means on said frame spaced from its pivotal axis so as to present a held workpiece to the tool when the frame is rocked in one direction to an operating position, a cam supported on said frame in axial alignment with the workpiece, said cam having a surface of revolution derived from a pattern exhibiting the contour to be reproduced on the workpiece, a cam follower on said base engageable by said cam, said cam and follower coacting to vary the position of the workpiece relative to said tool in accordance with said contour, means for rotating said work holding means and said cam in synchronism, a pressure fluid operated actuator adapted when fluid is supplied thereto to rock said frame from operating position to retracted position, said frame returning to operating position by gravity upon exhaust of fluid from the actuator, valve mechanism controlling the supply and exhaust of fluid to and from said actuator, said mechanism including a metering valve operative to control the exhaust of fluid from the actuator and thereby regulate the speed of movement of the frame toward operating position, and a check valve operative to establish a bypass around said metering valve and permit rapid

movement of the frame toward retracted position.

2. In a machine for operating on workpieces having complex curved surfaces of revolution, in combination, a base, a slide mounted on said base, a driven abrasive tool carried by said slide, a frame supported on said base for pivotal movement about an axis disposed at one side of said tool and for linear translation along said axis, work holding means on said frame spaced from its pivotal axis so as to present a held workpiece to the tool when the frame is rocked in one direction to an operating position, a cam supported on said frame in axial alignment with the workpiece, said cam having a surface of revolution derived from a pattern exhibiting the contour to be reproduced on the workpiece, a cam follower on said base engageable by said cam, said cam and follower coacting to vary the position of the workpiece relative to said tool in accordance with said contour, means for rotating said work holding means and said cam in synchronism, power actuated means for translating said frame so as to traverse the workpiece and cam axially relative to said tool and said follower, and control means including a second cam shiftable in timed relation to the rotation of said work holding means for coordinating the rate of movement of said frame with the rotative speed of said work holding means.

3. In a machine for finishing workpieces having complex curved surfaces, in combination, a base, a driven abrasive tool supported on said base, work supporting means mounted on said base for movement in a direction to feed the work to and retract it from the tool and in a direction to traverse the work past the tool, a work holding spindle supported on said work supporting means for rotation and for limited axial movement, means for rotating said spindle, power actuated means urging said work supporting means in said traversing direction, cam means operative incident to the rotation of said spindle for imparting axial movements to the spindle, a second cam normally positioned to block said work supporting means against movement by said power actuated means, and an actuator for withdrawing said second cam from said blocking position, said second cam being shaped to permit controlled movement of the work supporting means in such withdrawal.

4. In a machine for finishing workpieces having complex curved surfaces, in combination, a base, a driven abrasive tool supported on said base, work supporting means mounted on said base for movement in a direction to feed the work to and retract it from the tool and in a direction to traverse the work past the tool, a work holding spindle supported on said work supporting means for rotation and for limited axial movement, means for rotating said spindle, power actuated means urging said work supporting means in said traversing direction, cam means operative incident to the rotation of said spindle for imparting axial movements to the spindle, a second cam normally positioned to block said work supporting means against movement by said power actuated means, pressure fluid operated means for shifting said second cam to permit controlled movement of said work supporting means by said power actuated means, and control means associated with said pressure fluid operated means for regulating the rate of withdrawal of said second cam so as to coordinate its action with the action of said first cam and thereby

cause the tool to describe a predetermined path about the workpiece.

5. In a machine for finishing workpieces having complex curved surfaces, in combination, a driven abrasive tool, work supporting means including a frame swingable about an axis spaced laterally from said tool and for linear translation about said axis, a first power actuated means for swinging said frame between operating and retracted positions, rotary cam means for determining the operating position of said frame, a second power actuated means for translating said frame and said cam means, a work holding spindle rotatably supported on said frame, a motor for rotating said spindle and said cam means, and control mechanism including control devices for initiating and interrupting the operation of said power actuated means and said motor for effecting in sequence the swinging of said frame to operating position, rotation of the spindle with the workpiece in operative engagement with the tool, translation of the workpiece relative to the tool, swinging of the frame to retracted position, and translation of said frame back to starting position.

6. In a machine for finishing workpieces having complex curved surfaces, in combination, a driven abrasive tool, work supporting means including a frame swingable about an axis spaced laterally from said tool and for linear translation about said axis, a first power actuated means for swinging said frame between operating and retracted positions, rotary cam means for determining the operating position of said frame, a second power actuated means for translating said frame and said cam means, a work holding spindle rotatably supported on said frame, a variable speed motor for rotating said spindle and said cam means, and control mechanism including control devices associated with said power actuated means for effecting in sequence the swinging of said frame to operating position, rotation of said cam means and said spindle with the workpiece in operative relation with the tool, and translation of the workpiece axially relative to the tool, said mechanism also including control means for periodically varying the speed of said motor in timed relation to the rotation of said spindle.

7. In a machine for finishing workpieces having complex curved surfaces, in combination, means for supporting a workpiece for movement toward and from an abrasive tool, cam means controlling the position of the workpiece relative to the tool to determine the depth of cut taken by the tool, means for rotating the workpiece and said cam, means for imparting axial movement to the workpiece, and control mechanism for effecting in sequence rotation of the workpiece in engagement with the tool with the workpiece restrained against axial movement to cause the tool to describe a generally circular path around the workpiece, and simultaneous rotation and axial translation of the workpiece to cause the tool to describe a generally spiral path around the workpiece from one end to the other of the same.

8. A machine as set forth in claim 7 characterized by the provision of means in the control mechanism operative when the tool reaches said other end of the workpiece to shift the workpiece out of engagement with the tool and to interrupt its rotation.

9. In a machine for operating on workpieces having complex curved surfaces of revolution, in

combination, a base, a slide mounted on said base, a driven abrasive tool carried by said slide, a frame supported on said base for pivotal movement about an axis disposed at one side of said tool and for linear translation along said axis, a work holding spindle on said frame spaced from the pivotal axis of the frame so as to present a held workpiece to the tool when the frame is rocked in one direction to an operating position, a cam supported on said frame in axial alignment with the spindle, said cam having a surface of revolution generated from a pattern exhibiting the contour to be reproduced on the workpiece, a cam follower on said base engageable by said cam, said cam and said follower coacting to vary the position of the workpiece relative to said tool in accordance with said contour, means including a variable speed motor for rotating said spindle and said cam in synchronism, power actuated means for translating said frame to traverse the workpiece and cam axially relative to the tool and follower, a pair of electrical switches operable selectively to effect operation of said motor at different speeds, a disk mounted on and rotatable with said spindle, and switch actuating elements carried by said disk for actuating said electrical switches at predetermined points in the rotation of said spindle.

10. In a machine for operating on workpieces having complex curved surfaces of revolution, in combination, a base, a slide mounted on said base, a driven abrasive tool carried by said slide, a frame supported on said base for pivotal movement about an axis disposed at one side of said tool and for linear translation along said axis, a work holding spindle on said frame spaced from the pivotal axis of the frame so as to present a held workpiece to the tool when the frame is rocked in one direction to an operating position, a cam supported on said frame in axial alignment with the spindle, said cam having a surface of revolution generated from a pattern exhibiting the contour to be reproduced on the workpiece, a cam follower on said base engageable by said cam, said cam and said follower coacting to vary the position of the workpiece relative to said tool in accordance with said contour, means including a variable speed motor for rotating said spindle and said cam in synchronism, power actuated means for translating said frame to traverse the workpiece and cam axially relative to the tool and follower, a pair of electrical switches operable selectively to effect operation of said motor at different speeds, a third electrical switch adapted when actuated to stop said motor, a disk mounted on and rotatable with said spindle, and actuating elements for said switches mounted on and rotatable with said disk.

11. In a machine for finishing workpieces having complex curved surfaces, in combination, a base, a driven abrasive tool supported on said base, work supporting means mounted on said base for movement in a direction to feed the work to and retract it from the tool and in a direction to traverse the work past the tool, a work holding spindle mounted on said work supporting means for rotation and for limited axial movement relative thereto, means for rotating said spindle, power actuated means urging said frame in said traversing direction, a cam element normally positioned to block said frame against movement by said power actuated means, an actuator associated with said cam element and operative to

withdraw the element from blocking position at an adjustable predetermined rate, said cam element being shaped to permit controlled movement of the frame by said power actuated means incident to withdrawal of the cam.

12. In a machine for finishing workpieces having complex curved surfaces, in combination, a base, a driven abrasive tool supported on said base, work supporting means mounted on said base for movement in a direction to feed the work to and retract it from the tool and in a direction to traverse the work past the tool, a work holding spindle mounted on said work supporting means for rotation and for limited axial movement relative thereto, means for rotating said spindle, power actuated means urging said frame in said traversing direction, a control element normally positioned to block said frame against movement by said power actuated means and having a cam surface shaped to permit controlled movement of the frame by the power actuated means incident to the withdrawal of the element from blocking position, an actuator operable to withdraw said control element from blocking position, and means operative upon movement of the work supporting means in said feed direction for initiating operation of said actuator.

13. In a machine for finishing workpieces having complex curved surfaces, in combination, a base, a driven abrasive tool supported on said base, work supporting means mounted on said base for movement in a direction to feed the work to and retract it from the tool and in a direction to traverse the work past the tool, said work supporting means including a rotatable work holding spindle, power actuated means urging said work supporting means in said traversing direction,

5 10 15 20 25 30 35

tion, a control element normally positioned to block said work supporting means against movement by said power actuated means, pressure fluid operated means for shifting said control element away from blocking position to permit controlled movement of said work supporting means by said power actuated means, a metering valve associated with said pressure fluid operated means effective to regulate the rate of withdrawal of said control element and thereby coordinate the movements of the work supporting means with the rotation of the work holding spindle, means for reversing the operation of said power operated means to effect return of said control element to blocking position, and means for bypassing said metering valve during such reverse movement to effect return of said control element at a relatively high rate of speed.

HAROLD N. SEYFERTH.
